WINDOW BLIND

Patrick H. Dougherty, Waynesboro, Va.

Application February 28, 1939, Serial No. 258,977

8 Claims. (Cl. 156—17)

This invention relates to the art of window shades or blinds and particularly pertains to an improved Venetian blind in which the individual slats thereof are enveloped in readily removable covers comprised of glossy, flexible, non-fibrous sheeting or film.

One object of the present invention is to make Venetian blinds more available to the general public by making their actual use less expensive. Another object is to increase the artistic attractiveness of Venetian blinds now on the market. Another object is to prolong the time in which Venetian blinds may be kept serviceable and attractive. Another object is to produce a Venetian blind which has less tendency to become dirty and which may be more readily cleaned. A specific object of the invention is to furnish Venetian blinds that may be cheaply and readily renovated in accordance with the changing whims and fancies of the particular individual. A more specific object of the invention is to provide for the slats of Venetian blinds cheap, attractive covers which are so inexpensive they may be discarded and replaced with new covers to secure new ornamental effects as frequently as one may desire.

According to my present invention the individual slats of Venetian blinds are provided with a snug, smooth fitting, cover or wrapper made from glossy, flexible, non-fibrous, sheeting or film, such as ethyl cellulose or rubber hydrochloride sheeting or film.

In order to set forth clearly the present invention, reference is made to the following detailed description taken in connection with the accompanying drawing, wherein

Fig. 1 is a front perspective view of a Venetian blind supported from the frame of a window.

Fig. 2 is a perspective view taken on the line 2—2 of Fig. 1 of an individual slat enveloped in a film cover.

Fig. 3 is a vertical sectional view taken on line 3—3 of Fig. 2 and showing the individual slat enveloped in a film cover consisting essentially of a one place film sleeve.

Fig. 4 is a perspective view taken on line 2—2 of Fig. 1 in the modification of the invention wherein the individual slat is enveloped in a film cover consisting essentially of three separate film sleeves.

Fig. 5 is a vertical sectional view taken on line 5—5 of Fig. 4.

Fig. 6 is a vertical sectional view taken on line 5—5 of Fig. 4 in a modification of the invention wherein the slat is enveloped in a film cover con-

sisting essentially of a film sleeve made by a wrapping operation.

Referring to Fig. 1, a conventional Venetian blind is shown briefly for convenience. 1 is a window frame, 2 is a rather substantial wooden member attached rigidly to the window frame, 3 and 4 are bracket members attached to the wooden member, 5 is an upper swing board supported in the bracket members, 6 and 7 are front tape bands which together with rear tape bands (not shown) are attached to the upper swing board and extend vertically the length of the Venetian blind and are all fastened to the lower swing board 8. Each slat 9 is held in spaced relation by horizontally extending strings or tapes (not shown) attached to the front tape bands 6 and 7 and the corresponding rear tape bands. 10 and 11 are cords passed down through the perforations 12 and 13 in the slat members and fastened to the lower swing board, 14 is a slat lifting and lowering cord acting in conjunction with cords 12 and 13 through a standard pulley and runway (not shown) housed in member 2. 15 is a cord used to tilt the upper swing board and thereby the slats beneath to admit the desired amount of light.

Referring to the remaining figures, 16 is a one piece film sleeve provided with two perforations corresponding substantially to the same shape and size as the perforations 12 and 13 in the slat member; 17, 18, 19, and 20 are film sleeves, and 21 is a bonded joint of film to film.

In the preferred embodiment of the invention, a glossy, flexible, durable, non-fibrous, at least somewhat elastic film or sheeting, such as ethyl cellulose or rubber hydrochloride ones, is made in the form of a hollow ribbon or tube of the desired dimensions required for the slat to be covered. The resulting one piece sleeve 16 is drawn over the slat 9 so as to cover substantially the entire surface thereof smoothly and snugly. Two perforations, substantially coinciding with the size and shape of the perforations 12 and 13, are stamped in the sleeve cover at any suitable stage in the operations to provide for the passage of the 45 slat lifting cords 10 and 11. The readily removable sleeve 16 is preferably given a slippery finish on the side directly contacting the slat member to facilitate putting on the cover as well as subsequent removal at any time from the slat. Rubber 50 hydrochloride and like elastic films are particularly suitable for the purpose of the invention since such film covers may be slightly stretched in putting them on the slats without setting up excessive strains, hence may be more readily used 55

to give the snug smooth fit necessary to an attractive appearance. A commercially suitable manner of manufacturing the cover consists of forming a tube of rubber hydrochloride of considerable length, partially flattening or collapsing the tube, and cutting the partially flattened tube into sections corresponding in length to the slats to be covered.

In cases wherein the cover is made of a film material inherently lacking tear resistance and incapable of being perforated even with a heat sealing die without creating a definite weakness, the film cover is preferably made in a plurality of sleeve sections as shown in Fig. 4.

Another method of providing the slat with a film cover is to wrap a sheet of transparent film snugly around substantially the entire surface of the slat other than any small openings provided for passage of cords necessary in raising and lowering the slats of the blind. The free end edge of the wrapping is sealed, depending upon the base material of the film, with heat and/or pressure and/or suitable adhesive to the layer of film immediately beneath so as to present a smooth, strong bond as shown at 21 in Fig. 6. The film cover thus completed, encases smoothly and substantially precisely the contour of the slat. Any number of adhesives may be employed to make the necessary smooth bond; a generally useful composition being one, consisting essentially of a film-forming substance contained in a solvent and a suitable non-solvent diluent.

Still other ways of providing the film covers of the invention will be obvious to technicians, thus in the case of rubber hydrochloride and like films, the film sheet may be folded into the form of a wrapper of the required dimensions and the free end edge sewed to the body of the wrapper to give the desired cover.

Regardless of the manner in which the cover is made, one may either attach the cover firmly to the slat or may rely entirely on a snug fit to hold the cover mechanically in place. Preferably, however, the film cover is kept in a detachable condition to increase the flexibility permitted in renovating and changing the appearance of the Venetian blinds. The thickness of the film cover depends largely on the severity of conditions to which the Venetian blind is likely to be subjected. Thus, under mild to moderate conditions, one layer of .0005" film is perfectly satisfactory particularly if the film is a durable one and the slat has no glaring defects to be covered; whereas under harsh conditions, more than one layer of film having a thickness greater than .001" may be necessary.

The sheeting or film employed for the cover is preferably one which is adaptable to give a snug fit without setting up a strained condition leading to warpage of the slats or breakage of the film. Thus in place of ethyl cellulose or rubber hydrochloride, regenerated cellulose or a moisture-proofed regenerated cellulose film or sheeting of a suitable type may be substituted quite successfully. Or, if desired, a sheeting or film of benzyl cellulose, cellulose acetate, or cellulose acetopropionate of suitable characteristics may be employed. Likewise one may use for the purpose films made from vinyl resins, such as acetal and/or ester derivatives of polyvinyl alcohol, certain interpolymers of vinyl chloride and vinyl acetate, or films made from polyamide resins.

The films or sheetings are preferably transparent and colored, but they may be used in an uncolored condition if desired. Likewise the films

or sheetings may be pigmented with titanium dioxide, Prussian Blue, Monastral Fast Blue GS, Monastral Fast Blue BSN, Red Ochre, Chrome Yellow, etc. If the film is colored with dyes, a dye is preferably selected that is fast to light and water and that has a natural affinity for the base material of the film. In certain cases, such as in using rubber hydrochloride or vinyl acetate-vinyl chloride interpolymers, it is desirable to have present a small amount of mildly alkaline stabilizing agent. In certain cases, such as cellulose acetate film, it is desirable to apply to the surface of the film a slip and/or an antistatic agent, such as stearic acid. In most cases, plasticizers should also be incorporated in the films, particularly those made from cellulose derivatives.

The slats of the Venetian blinds are commonly made of lightweight wood. However they may be fashioned from various other materials, such as pressed cardboard, stiffened rubber, vulcanized fiber board, materials generically denoted as plastics, aluminum, or other lightweight metals.

The strings and tape bands employed in making Venetian blinds may be replaced by any suitable supporting means accomplishing the same objective; any number of which will suggest themselves to those familiar with the art. The tape bands, for instance, may be made of any suitable material which resists excessive elongation upon continued usage. Thus the tapes may be made from high strength regenerated cellulose yarn having an elongation of the order of 10% and a tenacity greater than 2.5 g. p. d. Or if desired, the same may be made of high tenacity regenerated cellulose film or the like.

The snug fitting, glossy film cover provided by the present invention, enables the production of an unusually large number of pleasing artistic effects while making use of Venetian blinds now on the market. Thus an otherwise monotonously drab room may be made quite cheerful and attractive by using Venetian blinds in which the slats are enveloped in blue film covers which reflect a bluish tone or tinge to the room. Breakfast nooks are made more cheerful by equipping the windows thereof with Venetian blinds in which the slats are encased in beautiful brilliant red film covers. Likewise children's nurseries may be ornamented with Venetian blinds in which the slats are enveloped with film covers which are colored red, green, blue, or any desired shade or mixtures of shades, or have thereon pictures of characters taken from Mother Goose tales, comics, and history. The improved Venetian blinds doubtlessly will find valuable utility in securing novel theatrical effects and in beautifying a great many other places than the home, such as offices, stores, hotel rooms, etc. Besides many artistic effects obtainable by the use of the film covers of the present invention, the resulting Venetian blinds have the advantages of not becoming dirty so rapidly as the Venetian blinds now on the market and of being more easily cleaned.

The film covers may be used to renovate the appearance of used Venetian blinds that are too costly to discard as soon as the blinds become soiled, frayed, or otherwise undesirable. The film covers may be manufactured at a fairly reasonable cost, hence may be discarded and replaced relatively inexpensively with new ones which may be selected to create a somewhat different appearance in a room and thereby relieve a monotonous sameness. In some cases the film covers may be put directly on the slats of a new Venetian

blind in order to preserve and also render the same more attractive.

Having now described fully my invention, it will be understood that I do not wish to be limited as to the scope of the invention other than by the spirit of the appended claims.

I claim:

1. As an article of manufacture, a cover for the slat of a Venetian blind, comprising a durable and somewhat elastic, removable, plasticized, non-fibrous, flexible film covering.

2. As an article of manufacture, a cover for the slat of a Venetian blind, comprising a durable and somewhat elastic, removable, plasticized, non-fibrous, flexible film covering characteristically adapted to fit the slat snugly without producing warpage of the slat.

3. As an article of manufacture, a cover for the slat of a Venetian blind, comprising a durable and somewhat elastic, removable, plasticized, flexible synthetic resin film covering.

4. As an article of manufacture, a cover for the slat of a Venetian blind, consisting of a removable,

partially collapsed one-piece tube, having substantially the same length and dimensions as the slat to be covered, said tube being comprised of a durable and somewhat elastic, flexible, non-fibrous film.

5. As an article of manufacture, a slat for Venetian blind, consisting of a slat-shaped member enveloped in a removable covering of a durable and somewhat elastic, flexible, plasticized, non-fibrous film.

6. As an article of manufacture, a cover for the slat of a Venetian blind, comprising essentially a durable and somewhat elastic, non-fibrous, flexible, polyamide resin film covering.

7. As an article of manufacture, a cover for the slat of a Venetian blind, comprising a durable and somewhat elastic, plasticized, non-fibrous, flexible ethyl cellulose film covering.

8. As an article of manufacture, a cover for the slat of a Venetian blind, comprising a rubber hydrochloride film covering.

PATRICK H. DOUGHERTY.
